UNITED STATES PATENT OFFICE.

FRED H. LOVELESS, OF CHICAGO, ILLINOIS, ASSIGNOR OF ONE-HALF TO LEROY M. FUDGE, OF HAMMOND, INDIANA.

SIGN.

Application filed August 26, 1922. Serial No. 584,423.

To all whom it may concern:

Be it known that I, FRED H. LOVELESS, a citizen of the United States, residing at Chicago, in the county of Cook and State of Illinois, have invented new and useful Improvements in Signs, of which the following is a specification.

My invention relates to signs and more particularly to a sign the display surface of which may be readily removed from its support for replacement or alteration of the inscriptions thereon.

The invention has for its primary object to provide in a sign of this kind a novel and improved means whereby the display surface is held in position upon its support against displacement without the employment of nails, screws or other conventional fasteners.

A further object of the invention is the provision of a sign of the kind stated which is simple in construction, inexpensive to manufacture, and which is capable of convenient and general application to all manner of objects to which signs are attached, such as trees, fences, street cars, vehicles and the like.

With the above and other objects in view as will become more apparent as the description proceeds, the invention comprises a novel combination and arrangement of parts to be hereinafter described and claimed, and in order that the same may be better understood, reference is had to the accompanying drawings forming a part of this specification.

In the drawings,

Figure 1 is a perspective view of a supporting frame to which the display surface of the sign is applied;

Fig. 2 is a similar view of the display surface;

Fig. 3 is a broken view in transverse section illustrating the display surface in place upon its support;

Fig. 4 is a section on the line 4—4 of Fig. 2;

Fig. 5 is an elevation showing the application of the sign to the side of a motor delivery vehicle;

Fig. 6 is a slightly modified form of the invention wherein the sign is depicted upon the curved front of a street car and,

Fig. 7 illustrates the manner of use of a plurality of signs upon an elevated railway waiting platform.

Referring specifically to the drawings, wherein like characters of reference designate like parts throughout the several views, numeral 10 denotes the upper and lower parallel rails of the supporting frame, they being connected by means of a cross piece 11 of thinner material which is fitted into opposed recesses in the back of the rails so that its outer face lies in the same plane therewith so as to present a smooth surface for more ready application of the frame to the object upon which it is to be located. Each of the rails 10 has a groove 12 extending throughout its outer longitudinal surface and the frontal edges of said rails adjacent said grooves are slightly rounded (as shown at 10^a in Fig. 3), the purpose of which will be presently described.

The removable display surface of the sign comprises a metal sheet 13 cut in substantially the same dimensions as the frame, the longitudinal edges of which terminate in opposed backward curls 14 which are adapted to be sprung over the rounded frontal edges of the rails into the grooves 12 to firmly locate the display surface upon the frame. Between the curls 14 and the plane surface of the sheet 13 is the inclined portion 15 which serves to draw the plane surface more firmly to the rails and at the same time hold the curls 14 seated in the grooves 12.

From the foregoing description read in connection with the accompanying drawings, the construction and utility of my improved sign will be readily understood. The display surface may be coated with a slate-like substance if desired and the advertising matter placed thereon with chalk or chalk paint, or the pasted paper sign may be placed thereon if preferred. If the sign is to be displayed from a post or tree, it will be secured thereto by means of nails driven through the cross member 11. When once positioned with its curls 14 in the grooves 12 of the rails it will be effectually so maintained against displacement by the wind, since a wind blowing from the back of the sign will only act to bulge the center of the display surface outward and cause the curls to more firmly grip the grooves while a wind blowing toward the front of the sign will press it against its frame.

The sign being in position, it may be readily removed and taken down by merely disengaging the lower curl 14 from its

groove whereupon the upper curl 14 may be raised and the sign lowered to the ground. Any change in the lettering thereon may then be conveniently made and the sign replaced obviating the necessity of doing the work from a ladder or in an unsteady or cramped position.

I have found it desirable in order to stiffen the metal display surface 13 to bend its end edges back as shown at 16 in Fig. 4. This also gives the ends a smooth edge and lends greater strength and stiffness to the curls 14.

In Figures 5, 6 and 7 various applications of the sign are illustrated. Fig. 5 shows the sign applied to the side of a commercial vehicle 17, while in Fig. 6 it is depicted upon the curved front of a street car. The frame in this case, also the display surface 13^a is curved to conform to the curve of the car front. The walls of station platforms are much used for advertising signs, it being highly desirable to use a readily removable and replaceable sign in connection therewith. Fig. 7 shows a portion of an elevated railway waiting platform 20 upon the walls 19 of which a plurality of signs embodying my invention are disposed.

While I have described and illustrated the preferred embodiment of my invention, it will be understood that various changes and modifications may be made in the same within the spirit of the invention, the scope of which is set forth in the following claims.

Having thus described my invention, what I claim as new and desire to secure by Letters Patent is:

1. In a sign, the combination with a support, of a display surface comprising a sheet of metal, and integral resilient clamping means associated with opposite edges of said display surface for removably locating it upon the support.

2. A sign of the character described comprising a pair of spaced parallel rails each of said rails having a longitudinal groove in its outer face, a display surface, and clamping means carried by opposite edges of said display surface engageable with grooves for removably locating said display surface thereupon.

3. A sign of the character described com-

prising a pair of spaced parallel rails, each of said rails having a longitudinal groove in its outer face extending throughout its length, a display surface positionable against said rails, and resilient clamping means carried by opposite edges of said display surface for engagement with said grooves for removably securing said display surface against said rails.

4. In a sign, the combination with a support, of a display surface having a plane inscription-bearing portion, resilient rearwardly directed curls carried by opposed edges of said display surface for engagement with said support, said curls being located beyond the plane portion of said display surface and rearwardly thereof, and the stock of said curls between said plane inscription bearing portion and said curls also presenting a substantially plane surface.

5. A sign of the character described comprising a pair of spaced parallel rails, each of said rails having a longitudinal groove in its outer face extending throughout its length, a sheet metal display surface removably carried against said rails, and integral rearwardly directed curls carried by opposite edges of said display surface engageable with said grooves for locating said display surface against said rails.

6. A sign of the character described comprising a pair of spaced parallel rails, each of said rails having a longitudinal groove in its outer face extending throughout its length, a sheet metal display surface having a plane inscription bearing portion, integral rearwardly directed curls carried by opposed edges of said display surface for engagement with said grooves, said curls being located beyond the plane portion of said display surface and rearwardly thereof, and the metal stock between said plane portion and said curls also presenting a substantially plane surface.

7. In a sign, a combination with a support of a display surface, an integral resilient clamping means associated with opposite edges of said display surface and extending throughout the length thereof for removably locating it upon the support.

In testimony whereof I affix my signature.

FRED H. LOVELESS.
